UNITED STATES PATENT OFFICE

160,084

FLOOR LAMP

Greta Magnusson Grossman, Beverly Hills, Calif.

Application December 24, 1949, Serial No. 6,836

Term of patent 14 years

(Cl. D48—20)

To all whom it may concern:

Be it known that I, Greta Magnusson Grossman, a subject of King George VI of England, residing in Beverly Hills, county of Los Angeles, and State of California, have invented a new, original, and ornamental Design for a Floor Lamp, of which the following is a specification, reference being had to the accompanying drawing, forming part thereof, in which,

Fig. 1 is a perspective view of a floor lamp, showing my new design.

Fig. 2 is a front elevational view thereof, the lamp shade being omitted.

The dominant features of my design are shown on the drawing in full lines.

I claim:

The ornamental design for a floor lamp, substantially as shown and described.

GRETA MAGNUSSON GROSSMAN.
